UNITED STATES PATENT OFFICE.

GABRIEL ABRAHAM, OF NEW YORK, N. Y.

SPRING-LINK BELT.

Application filed February 11, 1921, Serial No. 444,088. Renewed December 13, 1923.

To all whom it may concern:

Be it known that I, GABRIEL ABRAHAM, a citizen of the United States, and a resident of the borough of Manhattan, county, city, and State of New York, have invented certain new and useful Improvements in Spring-Link Belts, set forth in the following specification.

This invention relates to belts of the type 10 worn as a trouser support.

The object of the invention is to permit the fabrication of the belt proper from durable, substantially inelastic fabric, arranged in sections interconnected by resilient links, so that the belt as a whole is yieldable in response to undue tension and will take up to but not beyond a predetermined minimum. Although mere elasticity is of some advantage in a belt, it is not 20 an advantage to have indefinite elasticity such as that inherent in a tensed rubber band or extensive spring.

In carrying out the objects of the present invention, the belt proper may be made 25 in sections and the sections connected by resilient links normally held by a compression spring in their full take-up position, the take-up position determining the minimum circumference of the belt when 30 buckled.

The above and further objects of the invention will better be understood by reference to the illustrative embodiment to 35 which the following claim is directed, merely for purposes of illustration. This embodiment is described below in connection with the accompanying drawings, which form a part hereof, in which like characters designate corresponding parts in 40 the several parts, and in which—

Fig. 1 is a perspective view of a belt embodying the invention;

Fig. 2 is a front elevation, with parts broken away and drawn to an enlarged 45 scale, showing a resilient link of the invention; and

Fig. 3 is a section through line 3—3 of Fig. 2, looking in the direction of the arrows.

50 A body belt A is shown made up of sections of leather strap 1, 2 and 3, the sections 1 and 3 being detachably connectible in the usual manner by any convenient form of buckle 4. It is preferable that the 55 buckle 4 be the resilient buckle described

in my prior patent granted to me February 8, 1921, live buckle No. 1,368,009.

Resilient relief links B are employed to connect the belt sections 2—3 and 2—1. In fact, it should be understood that the 60 belt proper may be split up into as many sections as desired, with the sections connected by relief links B. In the drawings two are illustrated.

In this structure the link B comprises a 65 substantially rectangular plate 5, preferably of sheet metal and preferably somewhat curved, as indicated in Fig. 3, to fit better about the contour of the body. The plate 5 is formed along its opposite edges 70 with parallel, inturned guide flanges 6 and 7 and has a spring lip 8, inturned from its body portion 9, to form a retainer for the end 10 of the zigzag compression spring 11. Sliding within the flanges 6 and 7 of plate 75 5 is a slide-plate 12, which may have struck out flanges 13 and 14, tending to space it apart from the body portion 9 to form a working chamber for the spring 11. This slide-plate 12 likewise has a spring 80 lip 15 to be engaged by the end 16 of compression spring 11, so that the compression spring 11, reacting against the lips 8 and 15, tends to separate the plate 5 from the slide-plate 12. In the embodiment illus- 85 trated the end edges of the link B are provided with perforations 20 and 21 through which eyes 22 and 23 of bails 24 and 25 are fitted. The perforations 20 are positioned at a shorter distance from the spring retaining lip 15 of plate 12 than is the distance from the spring retaining lip 8 on plate 5 to the end of the body portion 9 of this plate 5 and a symmetrical positioning for the perforations 21 is made so that 90 the eyes 22 and 23 serve as stops to preserve the assemblment of the link while the bails 24 and 25 serve as convenient means to mount the looped ends 26 and 27 of the belt portions. Obviously the perforations 20 and 21 could be made of a size 95 to take the strap ends themselves, in which case the straps would serve as stops to preserve the assemblment of the link.

The compression spring 11 thus may 105 function solely as relief, its strength being sufficient to maintain the plates 5 and 12 in their normal position, shown in Fig. 2, until excessive strain is applied to the belt, in which case the spring 11 will yield under 110

compression temporarily to lengthen the belt A which, upon the removal of the undue strain, will resume its normal length without constriction beyond the degree desired.

What I claim and desire to secure by United States Letters Patent is:—

A resilient relief link for belts comprising an elongated plate having edge flanges spaced apart from and parallel with said plate and on one end a spring-retaining lip; a slide-plate sliding within said flanges and having an end spring-retaining lip; a compression spring reacting against said

spring-retaining lips and located between said plates; and one of said plates being provided with a perforation in its end at a shorter distance from its said spring-retaining lip than the distance from the spring-retaining lip of the other said plate to its end and a belt connection passing through said perforation and serving as a stop to lock the parts together.

In witness whereof I have signed my name to this specification, this 25th day of January, 1921, at New York, N. Y.

GABRIEL ABRAHAM.
